UNITED STATES PATENT OFFICE.

LEVI S. BROWN, OF WESTMINSTER, MARYLAND, ASSIGNOR OF ONE-HALF TO
ADOLPHUS C. RAHTER AND FRANK T. SHAW, BOTH OF SAME PLACE.

VEHICLE-AXLE.

SPECIFICATION forming part of Letters Patent No. 433,432, dated July 29, 1890.

Application filed June 11, 1890. Serial No. 355,069. (No model.)

To all whom it may concern:

Be it known that I, LEVI S. BROWN, a citizen of the United States of America, residing at Westminster, in the county of Carroll and 5 State of Maryland, have invented certain new and useful Improvements in Vehicle-Axes, of which the following is a specification, reference being had therein to the accompanying drawings.

This invention relates to certain new and useful improvements in axles for vehicles; and it has for its object to provide a two-part interlocking spindle by means of which all wear in the boxing of the hub is taken up, 15 thereby preventing rattling and wabbling of the wheel.

The invention consists of certain details of construction and combination of parts, all as more fully hereinafter described, shown in 20 the drawings, and pointed out in the claims.

Figure 1 of the drawings is a perspective view of the spindle. Fig. 2 is a longitudinal section of the same, showing the boxing thereon. Fig. 3 is a perspective view of the spindle, the two interlocking parts being separated.

Referring to the drawings, A represents the axle, upon the end of which is formed the rigid portion B of the spindle. This portion 30 B is somewhat shorter than the hub-boxing H and is turned down or otherwise slightly reduced in diameter upon its outer end for about half its length, as seen at 1, the remaining portion 2 being of sufficient diameter to neatly fit within the boxing.

In the periphery of the portion 2 of the spindle is formed a recess 3, for a purpose hereinafter described.

C represents the removable portion of the 40 spindle, which is designed to slide upon the reduced portion 1 of the fixed part B of the spindle; and it consists of a metal tube of a length corresponding with that of the reduced portion 1, and of such thickness that 45 when in place its periphery will be flush with that of part B. A tongue or lug c, formed integral with the inner end of the removable portion C, is designed to enter the recess 3, as seen in Fig. 1, which prevents the portion C 50 from revolving with the wheel. Upon the

outer end of the portion C is formed an annular flange 4, in the outer face of which is formed an annular recess 5, while on the inner face is formed an inwardly-projecting annular rim 6, said rim being of sufficient 55 diameter to overlap the end of the boxing.

A nut D, cast integral with a flange 7, is provided on its inner face with a projection 8, of sufficient diameter to neatly fit within the recess 5 of the removable portion of the 60 spindle. A screw-threaded shank E, cast integral with or otherwise secured to the inner face of the nut, projects inwardly and engages with a screw-threaded opening F in the outer end of the fixed portion B of the spindle. A 65 spiral spring G surrounds the screw-threaded shank E, and is designed to be interposed between the outer end of the fixed portion B of the spindle and the inner face of the nut. The pressure of the spring upon the nut, and 70 consequently upon the shank E, causes the threads of the latter to bind upon those of the opening F, thus locking the nut in any position it may be turned.

In placing the wheel upon the spindle the 75 nut and the removable portion C of the spindle are removed and the wheel is placed upon the fixed portion B. The removable portion C of the spindle is now placed over the reduced end of the fixed portion and pushed 80 inward until the inner face of the flange 4 abuts against the end of the boxing. The screw-threaded shank is now screwed into the opening F, against the pressure of the spring, until the flange on the nut comes into 85 contact with the end of the spindle, when it will be held in this position by the tension of the spring. The wheel is now ready for use. It will be seen that by this construction when 90 the boxing becomes worn upon its ends, and the wheel thereby becomes loose upon the spindle, it is only necessary to give the nut a slight turn, which forces the removable portion of the spindle farther into the boxing, thus making the spindle shorter and compensating for the wear of the boxing. A further 95 advantage in this construction lies in the fact that the wheel bears upon the inner face of the flange on the removable portion C of the spindle, which portion is held stationary, 100

as before described, thus rendering it impossible for the wheel to unscrew the nut, as is common in spindles of the ordinary construction, where the wheel bears directly upon the 5 nut. It will also be seen that the rim 6, overlapping the end of the boxing, forms a dust-guard for preventing sand, dust, and the like from getting on the spindle.

Having thus described my invention, what I 10 claim as new, and desire to secure by Letters Patent, is—

1. In a vehicle-axle having a two-part interlocking spindle, one part of which is formed integral with the axle, and has its outer portion reduced to a smaller diameter than its inner portion, the latter having a recess in its periphery, the other part being tubular in form and provided with a longitudinally-projecting tongue, the tubular part fitting over 15 the reduced portion of the rigid part and the tongue engaging with the said recess, for the purposes stated.

2. In a vehicle-axle having a two-part interlocking spindle, the combination, with the 20 fixed part of the spindle, whose outer portion is plain and of less diameter than its inner portion, said fixed part having a recess in the periphery of the larger portion and a screw-threaded opening in the end of the reduced 25 portion, of the tubular part of the spindle, adapted to fit over said reduced portion and having a longitudinally-projecting tongue to engage in said recess, and a flanged nut having a screw-threaded shank, the shank taking 30 into the opening in the end of the fixed part, and the flange bearing against the end of the tubular part, as described, and for the purposes stated.

3. In a vehicle-axle having a two-part interlocking spindle, the combination, with the 35 hub-boxing and the fixed part of the spindle, which is shorter than the hub-boxing, and has a recess in the periphery of its inner portion,

of the tubular part of the spindle, having a longitudinally-projecting tongue for engaging 45 with the recess in the fixed part, and provided with a flange upon its outer end, said flange having an annular rim upon its inner face adapted to fit over the hub-boxing, and a flanged nut having a screw-threaded shank, 50 which engages with the fixed and movable parts of the spindle to hold them together, for the purposes set forth.

4. In a vehicle-axle having a two-part interlocking spindle, the combination, with the 55 hub-boxing and the fixed part of the spindle, which is shorter than the hub-boxing and has a recess in the periphery of its inner portion and a screw-threaded opening in its outer end, of the tubular part of the spindle having a 60 longitudinally-projecting tongue for engaging with the recess in the fixed part and provided with a flange upon its outer end, said flange having an annular recess in its outer face and an annular rim upon its inner face, 65 and a nut having a screw-threaded shank for engaging with the opening in the end of the spindle, and provided with an integral flange having a projection upon its inner face adapted to fit in the recess in the outer end of the 70 tubular part of the spindle, for the purposes set forth.

5. In a vehicle-axle having a two-part spindle constructed as described, a nut provided 75 with a flange for engaging with the tubular part of the spindle, and a screw-threaded shank for engaging with the fixed part of the spindle, and a coiled spring surrounding the shank, substantially as described, and for the purposes stated.

In testimony whereof I affix my signature in presence of two witnesses.

LEVI S. BROWN.
